(57) CLAIM

The ornamental design for an iron club head, as shown and described.

DESCRIPTION

FIG. 1 is a rear perspective view of a iron club head;

FIG. 2 is a front elevational view thereof;

FIG. 3 is a top view thereof;

FIG. 4 is a rear elevational view thereof;

FIG. 5 is a bottom plan view thereof;

FIG. 6 is a heel elevational view thereof; and,

FIG. 7 is a toe elevational view thereof.

The broken line showing is for illustrative purposes only and forms no part of the claimed design.
